UNITED STATES PATENT OFFICE.

DAVID C. LAMB, OF NAPPANEE, INDIANA, ASSIGNOR TO LAMB BROS. & GREENE, OF NAPPANEE, INDIANA, A CORPORATION OF INDIANA.

PORTABLE ELECTRIC-LIGHT SUPPORT.

1,121,928.

Specification of Letters Patent. Patented Dec. 22, 1914.

Application filed July 18, 1914. Serial No. 850,653.

To all whom it may concern:

Be it known that I, DAVID C. LAMB, a citizen of the United States of America, and a resident of Nappanee, in the State of Indiana, have invented a new and useful Improvement in Portable Electric-Light Supports, of which the following is a specification.

This invention in its proposed embodiment is in part additional to the improvement in electric light supports set forth in my specification forming part of my application for U. S. patent filed March 20, 1914, and allowed June 13, 1914, Serial No. 826,032. (Patented July 28, 1914, No. 1105083.)

The present invention relates exclusively to portable electric lights, and consists in an improved support, of a stand type, and at the same time conveniently self-attaching, provided with a cord take up and with means for varying at will the angle at which the lamp bulb, with or without a superposed shade or reflector, is supported; all as hereinafter particularly described and claimed.

Two sheets of drawings accompany this specification as part thereof.

Figure 1 is an elevation of the improved device, in full and dotted lines, showing different adjustments of the same as used on a table or the like; Fig. 2 is a bottom view projected from Fig. 1; Figs. 3 and 4 are small scale views of the same device showing it respectively as hung on a nail and as attached to a rod or the like with the lamp in different positions; Fig. 5 is an elevation at right angles to Fig. 1; Fig. 6 represents a vertical section on the line A—B Fig. 5; Figs. 7 and 8 represent horizontal sections on the lines C—D and E—F Fig. 6 respectively; Fig. 9 is a perspective view of the reel detached; and Fig. 10 is a fragmentary section showing the reel brake and its spring.

Like reference characters refer to like parts in all the figures.

The improved device comprises a recessed wooden base *a*, a superposed metallic reel housing *b*, fixedly attached to said base by wood screws, a reel spring *c*, Figs. 6 and 7, coiled within an upper recess of said base, and attached to said base at one end; a cord reel, *d*, and a hollow spindle, *e*, therefor, inseparably united; a bell-crank-lever

brake, *f*, with its screw pivot, *g*, and spring *h*, Fig. 10, and a hinged tubular stem preferably and conveniently composed of lower and upper members *i*, *j*, with a frictional hinge joint *k* the axis of which is horizontal; said lower member being coupled endwise to said spindle *e* and said upper member to a commercial lamp socket *l*, which in turn receives a commercial lamp bulb, *m*, while the latter supports a shade or reflector *n* adjustable as to position thereon or removable at will as shown in Fig. 1.

A conductor-inclosing cord, *o*, of any required length, extends from a plug, *p*, Fig. 1, through openings, 1, 2, 3, in one side of the housing *b*, in the hollow hub of the reel *d* and at a corresponding point in the spindle *e* within said hub, respectively, into said spindle, and lengthwise within the latter and said tubular stem members *i* and *j*; its bifurcations extending loosely around the stem of the hinge joint *k* and through the upper stem member *j* to the respective terminals within the socket *l*.

The reel spring *c* being preferably and conveniently a flat coil of ribbon steel, engages a longitudinal slit, 4, Fig. 9, in the lower end of the spindle *e*, and tends to keep the cord *o* wound upon the reel *d*. When the required length of the cord *o* is drawn out from within the housing *b* through its aperture 1 the reel *d* is automatically fastened against the retraction of the cord by the brake *f*. For interaction with this brake, the reel *d* has upper and lower horizontal disks, 5 and 6, Fig. 9, of different diameters, suitably spaced apart by the hub member of the reel, the upper disk 5 clearing the brake *f*, which is pivoted within the housing *b* at one side as shown in Figs. 6 and 10, while the perimeter of the lower disk 6 projects radially beneath the brake *f*, and is effectively engaged by a curved camming surface 7, Fig. 10, at the lower end of the brake, under the action of the brake spring *h*, Fig. 10. The reel is released for the retraction of the cord by tilting the brake lever *f* on its pivot screw *g*, by finger pressure on its upper end or finger piece 8, Fig. 10, which protrudes upwardly through a slot 9, Fig. 10 in the top of the housing *b*.

The base *a* is preferably and conveniently rendered self-attaching to a table top, shelf or the like, represented at *q* Fig. 1, an up-

right rod or bar, *r*, Fig. 4, and other like objects, in the manner set forth in said previous specification (Patent No. 1,105,083); that is to say its bottom, Fig. 2, is provided 5 with a transverse groove, 10, within which a resilient member in the form of a normally straight flat bar, *b'*, is fastened at midlength by a wood screw 11; the ends of said bar protruding and being provided with rigid 10 arms *a'* and *a''* parallel with each other, adapted to engage the bottom of said table top, shelf or the like *q* as in dotted lines at *a'* and *a''* in Fig. 1, or said rod or bar *r* as in Fig. 4, so that the same is clamped by 15 the resiliency of said bar *b'* against the bottom of said base *a*; said bottom being further provided preferably with a felt cushion, 12, said arms *a'* and *a''* with cushioning sleeves, 13, of rubber tubing, and said bar 20 *b'* with edge cushions, 14, of flat rubber as described in said previous specification. A reinforcing leaf spring, represented at *s* in Fig. 2, is clamped into engagement with said bar *b'* by said screw 11. A hole, 15, Figs. 2 25 and 3, or its equivalent, at or near one edge of the base *a*, conveniently provides for hanging the device on a nail, *t*, or the like, as represented in Fig. 3. When thus hung against a wall, or when attached to an up- 30 right rod or bar as in Fig. 4, it is especially advantageous to be able to turn the stem member *j* on the axis of the hinge joint *k* so that the light bulb *m* hangs down as in dotted lines in Fig. 4. The hinge joint is 35 also advantageous when the device is used on a table or the like as in Fig. 1 for adjusting the light bulb *m* and its said superposed shade or reflector *n* with reference to a book or the like, and so as to suit and protect the 40 eyes of the user. Such shade or reflector *n* is preferably substantially hemispherical in shape, and provided with a pair of circularly curved resilient wires, 16 and 17, Figs. 1 and 5, between which the light bulb *m* is 45 lightly and at the same time securely clamped, so as to form, in connection with the bulb *m*, a universal joint of ample scope.

The cord *o* and plug *p* may be of known or improved construction. Their details 50 and those of the socket *l*, lamp *m*, shade or reflector *n*, attaching devices (*a'*, *a''*, *b'*, *s*) and the frictional hinge joint *k*, form no part of the invention hereinafter claimed. These details obviously admit of numerous 55 immaterial changes; and other like modifications will suggest themselves to those skilled in the art.

The term "wooden" as herein used is intended to include materials equivalent to 60 wood, such as solidified plastic compounds.

Having thus described said improvement, I claim as my invention, and desire to patent under this specification:

1. A portable electric light support hav- 65 ing, in combination, a recessed wooden base,

a superposed reel housing fixedly attached to said base and provided with a lateral aperture, a cord reel within said housing having an apertured hub and a vertical axis, an apertured hollow spindle upon which said reel is fast, a tubular stem forming an upwardly extending continuation of said spindle, the terminal inclosing socket of an incandescent electric light communicating with the interior of said stem and rotatable 70 with said reel, a conductor inclosing cord windable upon said reel, a cord-winding spring within said base engaging said spindle, and a brake within said housing engaging said reel, said cord extending through 80 the apertures of said housing, hub and spindle, and axially within said spindle and stem to the terminals within said socket, and its surplus length being automatically wound upon said reel by said spring under the control of said brake.

2. A portable electric light support having, in combination, a recessed wooden base, a superposed reel housing fixedly attached to said base and provided with a lateral 90 aperture, a cord reel within said housing having an apertured hub and a vertical axis, an apertured hollow spindle upon which said reel is fast, a tubular stem the lower end of which communicates with said hollow 95 spindle and is attached thereto, the terminal inclosing socket of an incandescent electric light communicating with and fixedly attached to the upper end of said stem, a cord-winding spring within said base engaging 100 said spindle, a bell-crank-lever brake pivoted within said housing at one side and constructed with a camming surface at its lower extremity and an upwardly protruding finger end, said reel having an upper disk 105 which clears said brake and a lower disk the perimeter of which projects beneath said brake and is engaged by said camming surface, and a brake applying spring within said housing.

3. A portable electric-light support having, in combination, a recessed wooden base, a superposed reel housing fixedly attached to said base and provided with a lateral aperture, a cord reel within said housing comprising horizontal disks suitably spaced apart by an apertured hub member, an apertured hollow spindle upon which said reel is fast, the terminal inclosing socket of an incandescent electric light rotatable with 115 said spindle and reel, a conductor inclosing cord extending through the apertures of said housing, hub and spindle to said socket and windable upon said reel, a cord-winding spring within said base engaging said spindle, and a spring-pressed brake within said housing normally engaging one of said disks 120 of the reel.

4. A portable electric-light support hav- 125 ing, in combination, a recessed wooden base,

- a superposed reel housing fixedly attached to said base and provided with a lateral aperture, a cord reel within said housing comprising horizontal disks suitably spaced apart by an apertured hub member, an apertured hollow spindle upon which said reel is fast, the terminal inclosing socket of an incandescent electric light rotatable with said spindle and reel, a conductor inclosing 10 cord extending through the apertures of said housing, hub and spindle to said socket and windable upon said reel, a cord-winding spring within said base engaging said spindle, a bell-crank lever brake pivoted within said housing at one side and constructed with a camming surface at its lower extremity and an upwardly protruding finger end, and a brake applying spring within said housing, the perimeter of the lower 15 disk of the reel projecting beneath and engaging said camming surface.
5. A portable electric-light support having, in combination, a base recessed at its top, a superposed reel housing fixedly attached to said base and provided with a lateral aperture, a cord reel within said housing having an apertured hub and a vertical axis, an apertured hollow spindle upon which said reel is fast having a slotted lower end, a terminal inclosing socket rotatable with said spindle and reel, a conductor inclosing cord extending through the apertures of said housing, hub and spindle to said socket, and windable upon said reel, a 20
- 25
- 30
- cord-winding spring in the form of a flat 35 coil of ribbon steel within the recess of said base engaging said slotted end of the spindle, and means for yieldingly holding said reel against rotation.
6. In combination with a recessed wooden base and a superposed metallic housing fixedly attached thereto, a cord reel within said housing having a hollow hub and a vertical axis, a hollow spindle fast within said hub, said housing, hub and spindle having 40 communicating apertures, a subjacent reel spring within said base engaging the lower end of said spindle, a reel brake within said housing, a tubular stem attached to and communicating with said spindle, and the 45 socket of an incandescent electric light communicating with and fixedly attached to the upper end of said stem.
7. In combination with an attaching device a recessed wooden base the bottom of 50 which is provided therewith, a superposed housing, a cord reel rotatable within said housing, a reel spring within said base, a reel brake within said housing, a spindle and stem rotatable with said reel, the socket 55 of an incandescent electric light fixedly attached to the upper end of said stem, and a light bulb held in said socket, substantially as hereinbefore specified.
